TREATMENT OF BUTANE

Vladimir N. Ipatieff and Herman Pines, Chicago,
Ill., assignors to Universal Oil Products Company,
Chicago, Ill., a corporation of Delaware

No Drawing. Application December 28, 1940,
Serial No. 372,174

11 Claims. (Cl. 260—683.5)

This application is a continuation-in-part of our co-pending application Serial No. 103,383 filed September 30, 1936.

This invention relates to the treatment of butane of normal or straight-chain structure.

In a more specific sense, the invention is concerned with a process whereby normal butane is converted into isobutane, the process involving the use of special catalysts and particular conditions of operation which favor the isomerization reactions so that relatively high yields of the iso-compound are produced.

Since the invention is concerned principally with the two 4-carbon atom paraffin hydrocarbons and their transformation, one into the other, the following table is introduced to indicate the structure and the principal physical characteristics of these two compounds:

Properties of butanes

Name	Structure	B. P., °C.	Critical temperature, °C.	Critical pressure atmos- pheres
n-Butane.....	CH ₃ CH ₂ CH ₂ CH ₃	+0.5	151	36
i-Butane.....	CH ₃ CH—CH ₃ CH ₃	-10.5	134.5	37

Butanes are produced in considerable quantities in the oil refining industry. They occur in substantial amounts in natural gases (in which the normal compound usually predominates), in refinery gases which are evolved from crude petroleum storage tanks, and in the primary distillation of crudes, and they are also present in considerable percentages in the gases produced incidental to cracking heavy petroleum fractions for the production of gasoline. In the case of cracked gas mixtures the relative proportions of iso- and normal butanes vary, but the ratio of the iso to the normal compound is as a rule considerably higher than in natural gas.

Butanes may be considered as more or less marginal compounds in respect to their desirability in ordinary gasoline, that is, a certain percentage of them is essential for sufficient vapor pressure to insure ease in starting, while an excess tends to produce vapor lock. For these reasons the total percentage of 4-carbon atom hydrocarbons is commonly adjusted in conjunction with the boiling range and vapor pressure of the other gasoline components to produce a gasoline

of desirable starting characteristics according to seasonal demands.

The butanes at the present time bear a further important relationship to oil refining in that their excess production is being utilized as a source of gasoline either by ordinary thermal cracking or by special catalytic dehydrogenation processes followed by polymerization in which catalysts may or may not be used. Investigations have shown that iso-butane is considerably more amenable to cracking and dehydrogenation, both with and without catalysts, than the normal compound. Considering the corresponding mono-olefins, the normal butenes are considerably more difficult to polymerize, either thermally or catalytically, than iso-butene, and it is found also that the octenes representing the dimers of the isobutene are of higher antiknock value than those from n-butenes which holds also for the octanes produced by hydrogenation. It is, therefore, of considerable importance at the present time to convert as much as possible of the normal butane production into iso-butane, and the present invention is especially concerned with a process for accomplishing this object.

In one specific embodiment the present invention comprises the treatment of normal butane for the isomerization thereof into isobutane with catalysts comprising essentially aluminum chloride and aluminum bromide along with minor amounts of hydrogen chloride and/or hydrogen bromide at temperatures and pressures adequate to effect the desired isomerization to a substantial extent.

We have determined that by the use of the class of composite catalysts mentioned, and particularly by the convenient use of selected combinations of temperature and pressure normal butane may be converted into iso-butane with a yield of as high as 60% to 65%. By properly proportioning the aluminum chloride and aluminum bromide, regulating the amount and proportions of hydrogen chloride and hydrogen bromide added to the reaction zone and utilizing proper combinations of temperature and pressure, we have determined that normal butane may be isomerized to iso-butane to practically any desired extent, particularly when using hydrogen in the reaction zone to depress any desired side reactions. As a rule, temperatures of from 0 to 150° C. will be employed and pressures from about atmospheric to about 50 atmospheres. Using the preferred catalysts and selected conditions of temperature and pressure it has been found that it is possible to minimize undesirable side reactions

other than isomerization which otherwise results in the formation of hydrogen and hydrocarbons of both higher and lower molecular weight than the desired isobutane.

The invention comprises the use of mixed aluminum chloride-aluminum bromide catalyst in any desired proportions either in granular form or deposited upon granular supported materials. Aluminum bromide has been found to be generally a more powerful isomerization catalyst than aluminum chloride at a given temperature and has been found to be considerably more soluble in liquid normal butane than aluminum chloride. For example, at temperatures slightly below its boiling point, normal butane dissolves about 30% aluminum bromide by weight, while aluminum chloride is substantially insoluble therein. A further control in the present process is offered in the use of proportioned mixtures of hydrogen chloride and hydrogen bromide in isomerization reaction zones. The use of hydrogen up to a critical amount depending upon the type of activity of the catalyst composite employed prevents undesirable side reactions while amounts greater than this tend to depress or retard the isomerization reaction itself.

The process of the invention may be operated under batch or continuous conditions. Batch operations may be conducted by separately adding aluminum chloride, aluminum bromide, hydrogen chloride and/or hydrogen bromide and normal butane to a closed pressure container after which the container is agitated or the contents stirred mechanically while the temperature and pressure are maintained at an optimum point to produce a given yield production of the iso compound. This type of operation is better adapted to small scale production, while plants of considerable capacity are best operated in a continuous manner.

In continuous operations the butane may be pumped through a tubular heating element at a given temperature and pressure within the approximate ranges previously specified and reaction brought about along the line of flow by the separate or joint injection of proportioned amounts of aluminum chloride-aluminum bromide, hydrogen chloride and/or hydrogen bromide. In the absence of moisture there will be substantially no corrosion when using these catalyst composites. After passage through the heating element the reactants may be passed to enlarged insulated chambers for the completion of the desired isomerization and the total products subsequently fractionated to recover catalyst and separate the normal and isobutanes, after which the normal compound may be recycled for further treatment. Unused aluminum halides and hydrogen halides may also be recycled for further use.

Continuous operations may also be conducted by passing normal butane mixed with proportioned amounts of hydrogen chloride and/or hydrogen bromide through beds of heated, granular catalyst, which may comprise any proportions of aluminum chloride and aluminum bromide alone or preferably on relatively inert granular carriers. Among carriers which are readily utilizable may be mentioned activated carbon, clays, fuller's earth, alumina, bauxite silica alumina composites, diatomaceous earth and in general, refractory materials of the porous adsorbent character. Treatment of the products of the isomerization reactions in these cases will involve mere-

ly the condensation of the hydrocarbon products and the recycling of the hydrogen halides for further use.

In the preparation of granular catalysts comprising aluminum chloride-aluminum bromide composites on supports, a convenient method of preparation is to place a granular support such as activated carbon in a rotatable pressure vessel along with the desired amounts of aluminum bromide-aluminum chloride after which the pressure vessel is closed and hydrogen chloride and hydrogen bromide introduced under pressure. The contents of the pressure vessel are then heated to an elevated temperature with or without the addition of hydrogen or some substantially inert gas until the granular particles of the support are impregnated with the mixed halides. In these operations of manufacture, it is generally preferable to employ temperatures of the order of from 150 to 200° C. to insure proper distribution and penetration of the halides on granular particles. Aluminum bromide melts at 97.5° C. and boils at 268° C. while aluminum melts at 190° C. under 2.5 atmospheres pressure and sublimes at 178° C. at atmospheric pressure. In continuous operations with granular supported catalyst composites prepared in this manner, it is advantageous to employ sufficient amounts of the proportioned metal halides to substantially saturate granular particles at temperature and pressure of operation in order to get the maximum isomerizing effect from a given catalyst space.

In continuous operations it is comprised with in the scope of the invention to increase the temperature in reactors as the granular catalyst becomes spent or to increase the amount of hydrogen chloride and/or hydrogen bromide added, each expedient tending to compensate for the loss in catalytic activity.

The following data are introduced to illustrate the character of the results obtainable in the operation of the process of the invention but without the intention of unduly restricting its scope thereby:

A mixture consisting of 80 mols of normal butane, 10 mols of hydrogen, 5 mols of hydrogen chloride and 5 mols of hydrogen bromide is passed over a granular catalyst consisting of 80 percent by weight of granular alumina supporting 15 percent by weight of substantially anhydrous aluminum chloride and 5 percent by weight of aluminum bromide at a temperature of 90° C. and a pressure of 200 pounds per square inch. Under these conditions, using a liquid space velocity of normal butane corresponding to 2 volumes of liquid per volume of catalyst space per hour, it is found that there is a 40 percent conversion to iso-butane per pass over the catalyst, the ultimate yield of iso-butane obtained when recycling separated unconverted normal butane being 80 percent, the 20 percent difference being due to side reactions resulting in a formation of lighter and heavier materials.

We claim as our invention:

1. A process for the isomerization of normal butane to produce substantial yields of iso-butane therefrom which comprises subjecting said normal butane to contact with a catalyst comprising essentially aluminum chloride and aluminum bromide.

2. A process for the isomerization of normal butane to produce substantial yields of iso-butane therefrom which comprises subjecting

said normal butane at a temperature of from about zero to about 150° C. to contact with a catalyst comprising essentially aluminum chloride and aluminum bromide.

3. A process for the isomerization of normal butane to produce substantial yields of iso-butane therefrom which comprises subjecting said normal butane at a temperature of from about zero to about 150° C. at a pressure of from about atmospheric to about 750 pounds per square inch to contact with a catalyst comprising essentially aluminum chloride and aluminum bromide.

4. A process for the isomerization of normal butane to produce substantial yields of iso-butane therefrom which comprises subjecting said normal butane mixed with proportioned amounts of hydrogen chloride and hydrogen bromide at a temperature of from about zero to about 150° C. at a pressure of from about atmospheric to about 750 pounds per square inch to contact with a catalyst comprising essentially a proportioned mixture of aluminum chloride and aluminum bromide.

5. A process for the isomerization of normal butane to produce substantial yields of iso-butane therefrom which comprises subjecting said normal butane mixed with proportioned amounts of hydrogen chloride and hydrogen bromide at a temperature of from about zero to about 150° C. at a pressure of from about atmospheric to about 750 pounds per square inch to contact with a catalyst comprising essentially a proportioned mixture of aluminum chloride and aluminum bromide, the ratio of said aluminum chloride and said aluminum bromide being greater than 1.

6. A process for the isomerization of normal butane to produce substantial yields of iso-butane therefrom which comprises subjecting a mixture of hydrogen, said normal butane and proportioned amounts of hydrogen chloride and hydrogen bromide at a temperature of from about zero to about 150° C. at a pressure of from about atmospheric to about 750 pounds per square inch to contact with a catalyst comprising essentially a proportioned mixture of aluminum chloride and aluminum bromide.

7. A process for the isomerization of normal butane to produce substantial yields of iso-butane therefrom which comprises subjecting a mixture of hydrogen, said normal butane and proportioned amounts of hydrogen chloride and hydrogen bromide at a temperature of from about zero to about 150° C. at a pressure of from about atmospheric to about 750 pounds per square inch to contact with a catalyst comprising essentially a proportioned mixture of aluminum chloride and aluminum bromide, the ratio of said aluminum chloride and said aluminum bromide being greater than 1.

8. A process for the isomerization of normal butane to produce substantial yields of iso-butane therefrom which comprises subjecting a mixture of hydrogen, said normal butane

and proportioned amounts of hydrogen chloride and hydrogen bromide at a temperature of from about zero to about 150° C. at a pressure of from about atmospheric to about 750 pounds per square inch to contact with a catalyst comprising essentially a granular composite of a relatively inert support and a proportioned mixture of aluminum chloride and aluminum bromide.

10. A process for the isomerization of normal butane to produce substantial yields of iso-butane therefrom which comprises subjecting a mixture of hydrogen, said normal butane and proportioned amounts of hydrogen chloride and hydrogen bromide at a temperature of from about zero to about 150° C. at a pressure of from about atmospheric to about 750 pounds per square inch to contact with a catalyst comprising essentially a granular composite of a relatively inert support and a proportioned mixture of aluminum chloride and aluminum bromide, the ratio of said aluminum chloride and said aluminum bromide being greater than 1.

25. 10. A continuous process for the isomerization of normal butane to produce substantial yields of iso-butane therefrom which comprises subjecting a mixture of hydrogen, butane and proportioned amounts of hydrogen chloride and hydrogen bromide at a temperature of from about zero to about 150° C. at a pressure of from about atmospheric to about 750 pounds per square inch to contact with a catalyst comprising essentially a granular composite of a relatively inert support and a proportioned mixture of aluminum chloride and aluminum bromide, fractionating the products into a mixture comprising essentially hydrogen, hydrogen chloride and hydrogen bromide, iso-butane, normal butane, and spent granular catalyst, and recycling said mixture and said fractionated normal butane to further isomerization treatment.

11. A continuous process for the isomerization of normal butane to produce substantial yields of iso-butane therefrom which comprises subjecting a mixture of hydrogen, said normal butane and proportioned amounts of hydrogen chloride and hydrogen bromide at a temperature of from about zero to about 150° C. at a pressure of from about atmospheric to about 750 pounds per square inch to contact with a catalyst comprising essentially a granular composite of a relatively inert support and a proportioned mixture of aluminum chloride and aluminum bromide, the ratio of said aluminum chloride and said aluminum bromide being greater than 1, fractionating the products into a mixture comprising essentially hydrogen, hydrogen chloride and hydrogen bromide, iso-butane, normal butane, and spent granular catalyst, and recycling said mixture and said fractionated normal butane to further isomerization treatment.
